Attns.

UNITED STATES PATENT OFFICE.

FRED S. CARR, OF NEWTON, MASSACHUSETTS, ASSIGNOR TO CARR FASTENER COMPANY, OF CAMBRIDGE, MASSACHUSETTS, A CORPORATION OF MAINE.

FASTENER.

Application filed February 26, 1925 Serial No. 11,694.

This invention aims to provide an improved separable fastener particularly, though not exclusively, useful for securing carpets and the like to floors.

5 The construction herein disclosed is, in some respects, similar to that disclosed in my co-pending application Serial No. 81,862, filed January 16, 1926. In that application there is claimed generically certain principles embodied in the construction shown in the present application and, therefore, this application is limited to a specific embodiment of the invention. Therefore, reference is made to the above-referred to application wherein the 10 broad principles of the invention have been claimed generically.

In the drawings, which show one illustrative embodiment of my invention:—

20 Figure 1 is a plan view of a portion of a carpet showing the underlying fastener in dotted lines;

Fig. 2 is a section on the line 2—2 of Fig. 1, being partly in elevation;

25 Fig. 3 is a bottom plan view of the socket;

Fig. 4 is a top plan view of the socket;

Fig. 5 is a side elevation of the socket; and

30 Fig. 6 is a plan section of the fastener showing the maximum distortion of the wall of the socket during engagement of the socket with the stud.

Referring to the drawings, I have shown a separable fastener which includes a one-piece socket presenting an aperture surrounded by jaws shiftable to permit passage of the head 35 of a stud therebetween. The socket also presents integral means for attachment to a support.

The stud, as illustrated, presents a short head 1, a neck 2 and a base portion 3, and may 40 be secured to a floor 4 or the like by the usual type of attaching screw 5 as best illustrated in Fig. 2.

The socket is pressed from a single piece of 45 metal and comprises a casing having a peripheral wall 6 (herein shown as rectangular) and presenting a stud-receiving aperture 7 surrounded by a plurality of resilient fingers 8. The fingers extend inwardly from the lower edge of the wall 6 and are curved upwardly and outwardly at their inner ends to provide curved neck-engaging jaw portions 9. These neck-engaging portions 9 provide a rounded wall about the periphery of the stud-receiving aperture 7 which permits the 50 smooth engagement and disengagement of the

socket with the stud. The socket is cut away between the jaws to provide flexible portions 6^a in the wall 6 between the fingers 8. These portions 6^a are adapted to flex toward the center of the socket when a stud is forced between the jaws to spread them, as shown in Fig. 6. Thus the jaw portions 9 and fingers 8 may expand in a generally lateral plane rather than bend upwardly when a stud is being engaged with the socket, but, in order that such lateral movement may take place, the entire continuous wall 6 must be distortable. From the above it will be readily understood that the flexible portions 6^a between the fingers 8 permit the lateral distortion of the wall 6 during engagement and disengagement of the stud and socket.

The socket may be secured to a carpet 10 or the like, by a plurality of prongs 11 which extend upwardly from the wall 6 as best illustrated in Figs. 2 and 5. These prongs are preferably forced through the web of the carpet and are bent outwardly and downwardly (Fig. 2) so that they again pierce the web of the carpet 10 and form hooks over the warp 80 and weft threads of the web and are concealed by the pile of the carpet. Thus the hooks are remote from the neck-engaging portions 9 of the socket and therefore provide a favorable leverage for disengaging the socket from the 85 stud, when the carpet is pulled upwardly.

The wall 6 of the casing, as illustrated in Fig. 2, spaces the resilient fingers 8 and the neck-engaging portions 9, which are in substantially the same plane as the lower 90 edge of the wall 6, away from the carpet 10 to provide a space for the head 1 of the stud and also to provide means for permitting the jaws 9 to expand for the head of the stud to pass between them as hereinafter 95 more fully described.

When the stud and socket are engaged, the flat portions of the resilient fingers 8 rest against the base portion 3 of the stud, as illustrated in Fig. 2.

100 Engagement of the socket and stud may be effected by pressing upon the carpet directly over the socket, thereby contacting the jaw portions 9 with the head 1 of the stud. As pressure is applied to the socket, the jaws 105 9 open to enlarge the stud-receiving aperture 7. This spreading action is due partly to the slight resiliency of the fingers 8, but mostly to the flexibility of the wall portions 6^a at the corners of the socket. These cor- 110

ner portions of the wall permit lateral movement of the fingers 8 and jaw portions 9 by tending to straighten as the head of the stud is forced between the neck-engaging portions 9, as illustrated in Fig. 6. Thus it will be understood that the greater part of the movement of the jaw portions 9 is in a lateral direction rather than upward or downward. This fact permits the use of a smaller socket because the fingers may be greatly shortened in comparison with a socket where the upward and downward flexing of the fingers is entirely relied upon to permit passage of the head of a stud between them.

15 During the lateral distortion of the wall 6, the attaching prongs 11 are free to move the necessary slight distance because the warp and weft threads of the carpet are more or less flexible.

20 The peripheral wall 6 strengthens the socket, provides a durable spring means for the jaw members and permits the use of a smaller socket than could be used if the socket 25 were made entirely flat. Also the spring action of the wall at the corners, is much more desirable and efficient than could be obtained from the use of a flat socket.

While I have shown and described a preferred embodiment of my invention, it will 30 be understood that I have done so for purposes of clarification only, my invention being best defined in the appended claims.

I claim:

35 1. A one-piece fastener socket having a con-

tinuous upstanding peripheral rectangular wall portion having curved laterally yieldable portions at the corners thereof, a plurality of stud-engaging fingers extending inwardly from said wall at the sides thereof and having at their inner ends, surrounding a stud-receiving aperture, generally curved neck-engaging portions, said corner portions of said wall being more resilient than those portions of the wall located adjacent to the 45 stud-engaging fingers whereby the wall may be distorted and the stud-engaging fingers spread laterally to permit passage of the head of a stud therebetween.

2. A straight sided one-piece fastener 50 socket having a continuous peripheral wall providing the straight sides of the socket, a plurality of attaching prongs extending upwardly from said wall, stud-engaging jaws extending inwardly from the straight portions of the wall and surrounding a stud-receiving aperture and laterally yieldable curved corner portions of said wall connecting said straight portions, said corner portions being adapted to yield toward the center 55 of the socket thereby permitting lateral movement of the stud-engaging jaws and the straight portions of the wall outwardly with relation to the center of the socket thereby permitting enlargement of the stud-receiving 60 aperture for passage of the head of a stud between said jaws.

In testimony whereof, I have signed my name to this specification.

FRED S. CARR.
